United States Patent Office.

ABRAM ROWE, OF MACOMB, ILLINOIS, ASSIGNOR TO HIMSELF, CHARLES CHANDLER, AND JAMES DUNCAN, OF SAME PLACE.

Letters Patent No. 67,589, dated August 6, 1867.

IMPROVEMENT IN STEAM-GENERATORS.

The Schedule referred to in these Letters Patent and making part of the same.

TO ALL WHOM IT MAY CONCERN:

Be it known that I, ABRAM ROWE, of Macomb, in the county of McDonough, and State of Illinois, have invented certain new and useful Improvements in Steam-Boilers; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention consists in constructing a boiler, for generating steam, of a series of annular water-chambers, arranged concentrically one within another, with spaces for the heat to pass between them, and all opening direct into one common steam-chamber or reservoir.

Figure 1 is an elevation of a vertical boiler made on my plan, with a portion broken away to exhibit the interior.

Figure 2 is a top plan view of the same, with a portion broken away.

I construct a series of boilers or water-chambers, *c*, increasing in size from smallest to largest, in regular gradation, so as to form, when placed one within another, a regular series of concentric water-spaces, as represented in the drawings. These chambers are made slightly conical, being smallest at their upper end, as shown in fig. 1, and are arranged within a shell or outer case, *A*, which extends far enough above the chambers to form a steam-chamber, *C*, at the top. The inner wall of the outer chamber *c*, together with the shell *A*, also extends far enough below the bottom of the chambers *c* to form a furnace or fire-chamber, *F*, as shown in fig. 1, in which *o* represents the grate-bars, and *d* the furnace-door. By this arrangement it will be seen that the fire is surrounded by a water-chamber, which, together with each of the other chambers *c*, opens directly into the steam-chamber *C* at the top, as shown in fig. 1. At the bottom one or more series of tubes *n* connects the chambers *c*, so that the water may pass readily from one to another of the chambers; the tubes *n* being inclined downward, at their outer ends, for the purpose of causing the sediment to flow outward and be deposited in the outer chamber *c*, surrounding the furnace, from which it may be removed at the man-hole or opening *m*. When the series of chambers is thus arranged, there will be a central flue, *B*, passing from the furnace upward through the interior of the inner boiler *c*, which is closed at the top; the smoke passing through a lateral flue, *a*, as shown in fig. 1. There will also be an annular fire-space or flue, *b*, between each of the chambers *c*, each space or flue *b* being connected to the adjoining flue by a lateral flue, *a*, which is made larger than the one immediately preceding it, for the purpose of conveying the smoke which enters it from its own flue *b*, and also that which enters through the preceding flue. There may be two or more of these series of lateral flues *a*; all uniting outside of the boiler, in any desired manner, to form or enter the smoke-stack or chimney.

By this manner of constructing a boiler a large amount of heating surface is secured, and the whole arranged in an exceedingly compact manner. The heat, as it ascends, will impinge against the inclined surfaces and be rapidly transmitted to the water, and, by making the water-spaces *c* narrow, the water therein will be quickly heated, and thus generate steam with great rapidity.

It is obvious that horizontal boilers may be constructed on the same plan, by providing a steam-chamber above it, and connecting each of the chambers *c* therewith, in which case the flues *b* may extend directly through and enter the smoke-stack at the opposite end.

Having thus described my invention, what I claim, is—

A steam-boiler, consisting of a series of concentric chambers, *c*, opening at their upper end direct into a steam-chamber, and provided with the smoke-flues *a*, of a constantly increasing area from the centre outward; said chambers being connected by the lateral tubes or water-passages *n*, all constructed and arranged substantially as shown and described.

ABRAM ROWE.
